(Cl. D14—3)

To all whom it may concern:

Be it known that we, John C. Parkin and Stephen A. Bucholtz, citizens of the United States, residing at Snyder and Buffalo, respectively, in the county of Erie and State of New York, have invented a new, original, and ornamental Design for Motor Vehicle, of which the following is a specification, reference being had to the accompanying drawings forming part thereof.

Fig. 1 is a perspective view of a motor vehicle showing our new design;

Fig. 2 is a top plan thereof; and

Fig. 3 is a side elevational view thereof.

We claim:

The ornamental design for a motor vehicle, as shown.

JOHN C. PARKIN.
STEPHEN A. BUCHOLTZ.
